(57) **CLAIM**

The ornamental design for a chair for medical procedure, as shown and described.

DESCRIPTION

FIG. 1 is a front perspective view of a chair for medical procedure, showing our new design in a raised position; FIG. 2 is a front perspective view thereof in a partially lowered position;

FIG. 3 is a front perspective view thereof with one of the side rails in lowered position;

FIG. 4 is a left side elevation view thereof in a raised position;

FIG. 5 is a right side elevation view thereof;

FIG. 6 is a front elevation view thereof; and,

FIG. 7 is a top plan elevation view thereof.
